US00D856825S

(12) **United States Design Patent** (10) **Patent No.:** **US D856,825 S**
(45) **Date of Patent:** **** Aug. 20, 2019**

(54) **PARKING METER**

(71) Applicant: **Global Integrated Solutions Limited**,
Albany (NZ)

(72) Inventors: **Andrew Peter Ireland**, Christchurch
(NZ); **Michael Craig Shatford**,
Churchchrist (NZ)

(73) Assignee: **Global Integrated Solutions Limited**,
Albany (NZ)

(**) Term: **15 Years**

(21) Appl. No.: **29/570,171**

(22) Filed: **Jul. 6, 2016**

(30) **Foreign Application Priority Data**

Jan. 8, 2016 (NZ) 421089
(51) **LOC (12) Cl.** **10-03**
(52) **U.S. Cl.**
USPC **D10/42**

(57) **CLAIM**

The ornamental design for parking meter, as shown and described.

DESCRIPTION

FIG. 1 is a front perspective view of the parking meter; FIG. 2 is a bottom perspective view of the parking meter; FIG. 3 is a rear perspective view of the parking meter; FIG. 4 is a front elevational view of the parking meter; FIG. 5 is a rear elevational view of the parking meter; FIG. 6 is a side elevational view of the parking meter, the right and left sides being mirror images of each other; FIG. 7 is a top plan view of the parking meter; FIG. 8 is a bottom plan view of the parking meter; and, FIG. 9 is front perspective view showing the parking meter positioned on a post, the post being shown in phantom. The phantom lines in the drawings illustrate environmental structure that forms no part of the claimed design.

1 Claim, 8 Drawing Sheets
